UNITED STATES PATENT OFFICE.

WILLIAM E. WESTBERG, OF WILLMAR, MINNESOTA.

ENVELOP.

1,139,003.

Specification of Letters Patent.

Patented May 11, 1915.

Application filed May 2, 1914. Serial No. 835,966.

To all whom it may concern:

Be it known that I, WILLIAM E. WESTBERG, citizen of the United States, residing at Willmar, in the county of Kandiyohi and State of Minnesota, have invented certain new and useful Improvements in Envelopes, of which the following is a specification.

My invention relates to envelopes.

The primary object of my invention resides in the provision of an envelop used especially for sending out bills and packages in bakeries, ice cream plants, etc., having means detachably carried thereby for facilitating the location of the empty package or case, the means being detached before sending and filed in an index system.

Another object of my invention is to provide an improved blank for an envelop of the character described that is simple in construction, efficient in operation, and one that can be manufactured and placed on the market at a minimum cost.

Other objects as well as the nature, characteristic features and scope of my invention will be more readily understood from the following description taken in connection with the accompanying drawings and pointed out in the claim forming a part of this specification.

Referring to the drawings:—Figure 1 represents a top plan view of my invention; Fig. 2 represents a bottom plan view of my invention; Fig. 3 represents a sectional view taken on the line 3—3 of Fig. 1; and Fig. 4 represents a plan view of the blank used for forming an envelop.

Referring more particularly to the drawings wherein similar reference numerals designate corresponding parts throughout the different views, I provide a blank comprising a central or body portion 1 with side flaps 2 and 3, the latter having a gummed edge 4, to top flap 5 having a gummed edge 6 and a bottom flap 7. The bottom edge of the bottom flap 7 is cut diagonal to the body portion 1 as at 8 and is provided with a gummed edge 9 and a gummed side edge 10, the latter having extending therefrom a recording flap 11 which is made detachable by means of perforations 12.

In assembling the blank, the side flap 2 is folded upon the body portion 1 and side flap 3 is folded upon the body portion and the gummed edge 4 thereof is dampened and engaged upon the side flap 2. The bottom flap 7 is then dampened and secured in posi-

tion about the side flaps as clearly shown in Fig. 2 of the drawings. The recording flap 11 is then folded and is arranged upon the front face of the envelop as clearly shown in Fig. 1 of the drawings.

In order to provide a means for facilitating the attachment of the envelop to a container and for retaining a bill or the like within the envelop, I have positioned registering openings 13 through the central, side and bottom flaps and have secured about the opening on the outer face of the body portion 1 and the outer face of the bottom flap 7 strengthening eyelets 14.

In use, the name of the buyer is written or printed upon the front face of the body portion together with his address for facilitating the delivery of the package. The words "Return empty to" are also printed upon the envelop as a reminder. The recording flap 11 has printed thereon the words "Name—city—date and number", the name and city corresponding to the name and address printed on the front face of the body portion 1, the date being the date of the delivery of the container or package, the number corresponding to the number of the container and the front face of the envelop has also printed thereon the number of the container and corresponds with the number on the recording flap. Before delivery, the form being filled out as described, the recording flap is detached therefrom by means of the perforations 12 and filed away in an index system. The bill is placed in the envelop and a suitable fastening means such as a cord or the like passed through the opening 13 and the bill within the envelop and attached to the container, whereupon the latter is delivered. In the event that the empty container is not returned within the course of a reasonable length of time, the shipper will resort to his index system and in this manner determine the whereabouts of the container, whereupon the buyer is promptly notified and asked to return the same.

Although I have not set forth the kind of material used in forming this blank, it is advisable that the same have sufficient strength as not to be easily torn and be sufficiently stiff to facilitate the filing of the same.

It is thought to be obvious to those skilled in the art that it is not necessary to employ a card index system as I could have other

means for recording the flap and determining the whereabouts of the empty container.

From the above description taken in connection with the accompanying drawings it can easily be seen that I have provided a blank that is simple in construction that can be easily manufactured and when manufactured can be placed upon the market and sold at a minimum cost.

10 It will be understood that the above description and accompanying drawings comprehend only the general and preferred embodiment of my invention and that various minor changes in detail of construction, proportion and arrangement of the parts may be made within the scope of the appended claim and without sacrificing any of the advantages of my invention.

I claim—

20 An envelop formed from a blank of substantially stiff material comprising a substantially rectangular body portion adapted for the reception of an address, side flaps extending therefrom and foldable on the 25 rear face of the body portion, the outer longitudinal edge of one of the side flaps

being gummed for engagement with the other of the side flaps, a gummed top flap extending from the body portion and foldable thereon, a bottom flap projecting from the body portion and foldable thereon, the outer edge of the bottom flap being cut diagonal, a recording flap extending from the enlarged end of the bottom flap and foldable over the upper corner of the front face of the body portion and adapted for the reception of an address corresponding to the address on the front face, said recording flap provided with perforations adjacent the upper edge thereof for facilitating the disengagement of the recording flap from the bottom flap and said body portion, said flaps and bottom flap provided with registering openings for facilitating the attachment of the same to a container. 45

In testimony whereof I affix my signature in presence of two witnesses.

WILLIAM E. WESTBERG.
